UNITED STATES PATENT OFFICE

120,226

DESIGN FOR A TUMBLER OR THE LIKE

William J. Lundy, Olean, N. Y., assignor to Olean Glass Company, Olean, N. Y., a corporation of
New York

Application September 7, 1939, Serial No. 87,079

Term of patent 7 years

To all whom it may concern:

Be it known that I, William J. Lundy, a citizen of the United States and residing at Olean, in the county of Cattaraugus and State of New York, U. S. A., have invented a new, original, and ornamental Design for a Tumbler or the like, of which the following is a specification, reference being had to the accompanying drawing, forming a part thereof, wherein:

and

I claim:

The ornamental design for a tumbler or the like, as shown.

WILLIAM J. LUNDY.
